UNITED STATES PATENT OFFICE

153,004

DESIGN FOR A WRINGER

George F. Minnis, Chicago, Ill.

Application October 8, 1948, Serial No. 149,038

Term of patent 14 years

(Cl. D49—1)

To all whom it may concern:

Be it known that I, George F. Minnis, a citizen of the United States, residing at Chicago, in the county of Cook and State of Illinois, have invented a new, original, and ornamental Design for a Wringer, of which the following is a specification, reference being had to the accompanying drawings forming a part thereof.

In the drawings:

Fig. 1 is a perspective view of a wringer, embodying my new design.

Fig. 2 is a side elevational view of the wringer of Fig. 1.

Fig. 3 is a top plan view of the wringer of Fig. 1.

I claim:

The ornamental design for a wringer, as shown.
GEORGE F. MINNIS.
